N. T. McCLEER.
SLIDING DOOR FASTENER.
APPLICATION FILED MAY 4, 1908.

Patented Dec. 8, 1908.

FIG. 1.

UNITED STATES PATENT OFFICE.

NEIL T. McCLEER, OF GREGORY, MICHIGAN.

SLIDING-DOOR FASTENER.

No. 906,452.

Specification of Letters Patent.

Patented Dec. 8, 1908.

Application filed May 4, 1908. Serial No. 430,723.

To all whom it may concern:

Be it known that I, NEIL T. McCLEER, a citizen of the United States, residing at Gregory, in the county of Livingston and State of Michigan, have invented certain new and useful Improvements in Sliding-Door Fasteners; and I do hereby declare the following to be a full, clear, and exact description of the invention, such as will 5 enable others skilled in the art to which it 10 appertains to make and use the same.

This invention relates to latches for barns and other buildings; and it consists in the novel construction and combination of the 15 parts hereinafter fully described and claimed.

In the drawings, Figure 1 is a plan view of the latch, showing the door-post and a portion of the door in section. Fig. 2 is a front view of the latch.

20 A is a portion of the door-post, and B is a portion of the door which slides back and forth in the plane of the arrow in Fig. 1.

C is a metallic socket which is let into the front face of the door and which is provided with an inclined surface c next to the 25 edge of the door.

D is the main portion of the latch which is provided with a hole d at one end.

E is a staple, one leg of which engages 30 with the hole d, and which is driven into the door-post so that the part D is hinged to the door-post and is also free to move to a limited extent in a vertical plane.

F is a shoulder on the part D which 35 forms an abutment for the edge of the door to bear against when the door is closed.

The latch is provided with a tooth f at its opposite end from the hole d. This tooth has an inclined under surface f' for the edge 40 of the part c to strike against.

G is an eye at the end of the part D over the said tooth, which serves as a handle.

H is a rod provided with a screwthreaded 45 end portion h which engages loosely with a hole in the part D close adjacent to the shoulder F. Two nuts i are provided for securing the rod H to the part D and adjusting its position.

The rod H is slidable in a hole j in the 50 door-post, and it is provided with a knob

or handle I on the opposite end of it from the nuts. A spiral spring J is interposed between the knob I and the door-post. One end portion of this spring is preferably let into a recess in the door-post. 55

When the door is closed it engages automatically with the toothed end portion of the latch, and the spring J presses the door against the door-post so that it is weather-tight and cannot rattle. The latch can be 60 operated from either side of the door, and it does not project into the door-way when the door is open.

What I claim is:

1. The combination, with a door-post provided with a hole, and a slidable door having a socket at its edge; of a latch hinged to the said door-post at one end and provided at its other end with a shoulder for the edge of the door to bear against and a tooth for engaging with the said socket, a rod secured to the main portion of the said latch adjacent to the said shoulder and projecting through the said hole in the door-post and provided with a knob on its free 75 end, and a spring arranged between the said knob and the door-post.

2. The combination, with a door-post provided with a hole, and a slidable door having a socket at its edge; of a latch hinged 80 to the said door-post at one end and provided at its other end with a shoulder for the edge of the door to bear against and a tooth for engaging with the said socket, a rod having a screwthreaded portion at one 85 end and adjustable longitudinally in a hole in the main portion of the said latch adjacent to the said shoulder, nuts for securing the said rod in position, a knob on the free end portion of the said rod which projects through the said hole in the door-post, and a spring arranged between the said 90 knob and the door-post.

In testimony whereof I have affixed my signature in the presence of two witnesses. 95

NEIL T. McCLEER.

Witnesses:

ELDA A. KUHN,
L. K. McCLEER.
